DISASSEMBLABLE ARCHERY FINGER TAB

George D. Birnie, Pine Bluff, Ark., assignor to
Brunswick Corporation

Filed Feb. 28, 1973, Ser. No. 336,541

Term of patent 14 years

Int. Cl. D2—

U.S. Cl. D2—361

FIG. 1 is a perspective view of the back of a disassemblable archery finger tab showing my new design;

FIG. 2 is a palm side view thereof;

FIG. 3 is a side elevational view;

FIG. 4 is a side perspective view of one of the finger units disassembled from the strap portion;

FIG. 5 is a palm side view of the finger unit;

FIG. 6 is a back view thereof; and

FIG. 7 is a side view.

I claim:

The ornamental design for a disassemblable archery finger tab, substantially as shown and described herein.
